UNITED STATES PATENT OFFICE.

EDWIN CRAWLEY AND THOMAS L. BAYLIES, OF RICHMOND, INDIANA.

IMPROVEMENT IN VISES.

Specification forming part of Letters Patent No. 123,872, dated February 20, 1872; antedated February 16, 1872.

We, EDWIN CRAWLEY and THOMAS L. BAYLIES, of Richmond, county of Wayne and State of Indiana, have invented certain Improvements in Vises, of which the following is a specification:

Our invention, as hereinafter described, is designed as an improvement, in some of the details, upon the vise patented by us May 10, 1870; and relates to modifications in the construction of the bed-plate and box-slide, and also to modifications in the arrangement and manner of operating the pawl.

In the accompanying drawing, the vise is represented in the form best adapted to carpenters' and joiners' use.

With reference to the drawing, Figure 1 is a vertical longitudinal section through the center of the vise. Fig. 2 is a perspective view of the bed-plate detached from the bench and box-slide. Fig. 3 is a transverse vertical section through the dotted line xx of Fig. 1. Fig. 4 is a perspective view of the rear portion of the vise.

The other figures in the drawing will be hereinafter explained.

The same letters in the different figures refer to corresponding parts of the invention, or to parts the functions of which are similar.

B is the bench, to which the vise is attached, and forms the stationary jaw of the same. A is the movable jaw, which is secured to the box-slide C. G is the bed-plate, provided at its front end with the flange f , by means of which the vise is attached to bench B. On the sides of bed-plate G, and extending the entire length thereof, are formed tongues b b . On the lower edges of the sides of the box-slide are formed lips p p , which catch under tongues b b , and prevent the rear end of the box-slide from rising upward. Said lips p p may not extend the entire length of the box-slide, in which case the front end of the box-slide is prevented from moving upward by contact with the sides of the opening in bench B, through which the box-slide and bed-plate extend. The rear end of the box-slide is supported in proper position, with reference to the bed-plate, by nut H, which moves freely endwise within the box-slide. u u are projections formed on the side of that portion of bed-plate G which projects outward from the side of the

bench. The lower edges of the sides of the box-slide rest on said projections, by which means, in conjunction with tongues b b , lips p p , and nut H, the box-slide is maintained in proper position with reference to the bed-plate. This arrangement obviates the necessity of expensive machine-work in fitting the box-slide to the bed-plate, while, at the same time, a sufficiently accurate fit is obtained. v is a tie-rod, which extends from the lower end of flange f through a flange on the rear end of the bed-plate, by which means said bed-plate is strengthened. Pawl J is placed in a slot formed in nut H below screw-shaft E, and is centrally pivoted to said nut by pins s . a is a cam, which is secured to the rear end of said screw-shaft. r are ratchet-teeth formed on the upper surface of the bed-plate.

The operation of the mechanism is as follows: The parts being in the positions shown in Fig. 1, (pawl J being released from ratchet r ,) jaw A is free to be adjusted with reference to the article to be held in the vise. To secure an article in the same, the movable jaw is pressed against the article by the hand of the operator, and the operating-lever L is turned to the right. The first result of the rotary movement thus imparted to the screw-shaft E is to cause the projecting portion of cam a to recede from the rear end of pawl J, and permit said pawl to engage with ratchet r , which it does by reason of the greater weight of that portion of the pawl which is in front of pin s , over that portion which is in the rear of said pin. The engagement of the pawl with the ratchet prevents any further movement of nut H toward the front end of the vise; and the continued turning to the right of lever L causes the article to be compressed in the vise with a force due to the action of the threads on screw-shaft E with those in nut H. To release the article from the vise, lever L is turned to the left until the relative endwise movement between nut H and a given point on screw-shaft E has brought cam a in proper position to depress the rear end of pawl J as said shaft revolves, and thus disengage the pawl from the ratchet.

In the modification of devices for tripping the pawl, shown in Figs. 5 and 6 of the drawing, Fig. 5 being a longitudinal vertical sec-

tion through the center of the vise, showing the nut and pawl, together with a portion of the box-slide, bed-plate, and screw-shaft, and Fig. 6 being a perspective view of the rear portion of the vise, a pin, *a*, is substituted for the cam shown and described in the preceding example. Said pin is inserted in screw-shaft *E* near the rear end of the shaft, and projects at right angles to the axis of said shaft. The rear end of pawl *J* is turned upward to a position in which it may be struck and depressed by pin *a* when the pawl is to be released from ratchet *r*.

The operation of the mechanism is the same as the operation of that shown and described in the preceding example.

In Fig. 7 is shown another modification of devices for operating the pawl, the parts shown in the figure being similar to those shown in Fig. 5. Pawl *J* is pivoted to the front end of nut *H*. *g* is a rod, which slides in a suitable recess formed in said nut below screw-shaft *E*. The front end of said rod bears against a shoulder formed on the under side of pawl *J*. The opposite end of rod *g* projects beyond the rear end of nut *H*, and is bent so as to bring the extremity of the rod in proper position to come in contact with the front face of disk *a* when said pawl is to be released from ratchet *r*. Disk *a* is secured to the rear end of screw-shaft *E*. *o* is a spiral spring, which encircles rod *g*, the tension of which forces said rod away from pawl *J*. A groove and feather prevent rod *g* from turning in the nut.

When an article is to be compressed in the vise, lever *L* is turned to the right, by which means disk *a* is carried away from the end of rod *g* by the relative endwise movement between said disk and nut *H*, and the tension of spring *o* forces rod *g* backward, and permits pawl *J* to engage with ratchet *r*. The reversed movement of lever *L* bringing the face of disk *a* against rod *g*, the relative endwise movement between said disk and nut causes rod *g* to press against pawl *J* and release the latter from the ratchet, the tension of spring *o* being overcome.

In the modification shown in Fig. 8, the parts represented therein corresponding to those shown in the Figs. 5 and 7, the tripper *a* is made in the form of a frustum of a cone. Pawl *J* is similar in shape to that shown in Fig. 1. The pawl is tripped by coming in contact with the convexed portion of tripper *a*, the rear end of the pawl being carried downward, as it is caused to approach the greater diameter of the tripper, by the relative endwise movement hereinbefore described.

In Figs. 9, 10, 11, and 12 is shown another arrangement for supporting the front end of the box-slide, a pawl of a different construction from those hereinbefore shown and described, together with a change in the position of the ratchet. Fig. 9 is a longitudinal vertical section through the middle of the vise. Fig. 10 is a perspective view of the bed-plate detached from the bench and box slide. Fig. 11

is a transverse vertical section through the dotted line *xx* in Fig. 9. Fig. 12 is a perspective view of the pawl detached from the vise.

In the present example, the front end of box-slide *C* is supported by the post *t*, which is substituted for the projections *u u*, shown in the first example. Said post is secured to the bed-plate *G*, near the front of the latter, and extends upward sufficiently to permit the under side of the top of the box-slide to rest on the upper end of the post. Said post fits snugly within the interior of the box-slide, and is made sufficiently thick at the top to give a good bearing-surface, on which the box-slide moves. Screw-shaft *E* passes through an opening formed in post *t*, near the upper end of the same, and moves freely therein. The rear end of box-slide *C* is connected with the bed-plate by devices similar to those hereinbefore shown and described. If desired, the projections *u u* and post *t* may be used conjointly. In this example, the ratchet-teeth *r* are formed on the under side of bed-plate *G*. Pawl *J* is formed of the rectangular plate *i* and cross-bar *i'*. Said plate is pivoted at its upper edge to nut *H* by pins *s*, and moves freely in the slot *K*, formed in the bed-plate and extending nearly the entire length of the same. That portion of cross-bar *i'* which comes in contact with the ratchet-teeth *r* is properly formed to engage with said teeth. The cross-bar *i'* is attached to plate *i*, near the lower rear corner of said plate. The shape and functions of cam *a* are similar to the shape and functions of the cam shown in the first example. When the rear end of plate *i* is released from cam *a*, the superior weight of that portion of said plate which is forward of pin *s* causes the front end of the plate to descend and carry the rear end of the plate upward until the cross-bar *i'* engages with the ratchet-teeth *r*.

In the vise patented by us May 10, 1870, the pawl is tripped by means of a pin secured to the interior of the box-slide. In the arrangement herein shown and described, the tripper is secured on the rear end of the screw-shaft, which arrangement permits the parts to be more easily adjusted; and, in some of the modifications herein shown, the pawl responds to the movements imparted to the operating-lever more promptly than it does in the vise hereinbefore referred to patented by us.

In Figs. 13, 14, and 15 is shown a device whereby the pawl, when constructed as shown in Figs. 1, 5, 7, and 8, is prevented from engaging with the upper edge of a ratchet-tooth, and thereby rendering the latter or the edge of the pawl liable to be broken. Figs. 13 and 14 are longitudinal vertical sections through the center of the pawl and attachment, a portion of the ratchet also being shown. Fig. 15 is a perspective view of the attachment detached from the pawl.

This device consists of a preventer, *W*, placed in a slot formed in that portion of the pawl which is in front of the pin *s*, said preventer being pivoted by pin *s'* to the pawl. That por-

tion of the preventer which hangs perpendicular is prevented from swinging forward by reason of its contact with the front side of the slot in which said preventer is placed, but is free to swing in the opposite direction. The engaging part of the preventer is lower than the edge of pawl J that comes in contact with the ratchet, and the distance of said engaging point of the preventer from said edge of the pawl is a little less than the distance apart of a given number of ratchet-teeth. When the edge of the pawl would drop on the upper edge of a tooth, it is prevented from doing so by reason of the lower point of the preventer striking the upper edge of another tooth, as shown in Fig. 13. The parts being in this position, the endwise movement of nut H carries the pawl forward over the edge of the tooth which was immediately beneath the edge of the pawl, by reason of the forward end of the pawl being supported for the time by the preventer W; and as the forward movement of the nut is continued, the front end of the pawl will

move obliquely downward until the edge of the pawl comes in contact with the root of the next tooth in advance, as shown in Fig. 14.

We claim as our invention—

1. The tripper *a*, attached to the screw-shaft *E*, in combination with said screw-shaft, nut *H*, pawl *J*, and ratchet *r*, substantially as and for the purpose set forth.
2. The improved bed-plate *G*, comprehending the ratchet *r*, tongues *b b*, and shoulders *u u*, as described.
3. The combination, with said improved bed-plate, of the box-slide *C*, with flanges or lips *p p*, the nut *H*, and pawl *J*.
4. The combination of the preventer *W* with the pawl *J*, substantially as and for the purpose set forth.
